David Wunder and Charles Ruthven

Sewan, Illinois

The evidence referred to the Miss. Sewan Plant and making part of the evidence con-
-taining a description in the words of David Wunder and Charles
Ruthven themselves of their improvement in the machine for
-sifting and cleaning all kinds of grain.

The construction of this machine is small, is very plain and simple
and is as follows. First it consists of boards, 3 ft. 10 inches in length to 11 inches
wide stacked together 8 ft. 8 inches in width. The head of the wooden
board 2 ft. in diameter this is to be placed 44 inches from the bottom top
and 3 quarters of an inch from the back in front. the air-hole is to cut
11 inches in diameter an upper piece is to be placed perpendicular to it off
the air-hole; next a shaft is to be 20 inches in length from the side to the center
side board or iron at least 3" in thickness may be in wood, but iron or
other metal bars, four arms are put them so, that to revolve the front
are attached 8 inches in width extended so as to fill the space in the
wood board so board is to be covered with half inch stiff wire the 20
inches commencing 4 inches from the center on the top in front running
under the bottom and up the back and commence running the covering
12 inches back of the center on the top running 5 inches on the sides and
is continued on the same line two 24 inches towards the front from the
back end, and be bent from the top top down leaving a space for the
head 8 inches the stone is to be 12 inches in width 2 ft. 7 inches in length
the head and resting on a post, the bottom board, to pull sufficiently to
carry or slide down. the shaft side 14 1/2 upper side is visible 14 1/2 inches
bottom board, next side 14 1/2 inches below the middle so, that to be used in
pulling in front. Next a series of cheep wire meshing, commencing in front
post above the lower side descending back 12 inches, falling to the bottom
the side extending 8 inches further on a bed with the side more a space

174 inches which forms a spout sufficient to shake out the grain, Next a setting
steaming pipe running one eighth of an inch inside one foot in diameter
in the front of the bin this being tapered 3 inches at the small end, a head
is cut in this end, made there the bottom of the head on a side to
the left in diameter three inches a spout conveys the grain, how the
upper barrel which spout is fastened to the left side the barrel barrel
is supported with a shaft, and arms and rests in the center It moves up
and down in front of the wind barrel, the grain may be let out at the
left side the mill by hoisting a latch or down the slide the grain
to the setting barrel, the grain that goes there the setting barrel slopes
out the big end into a spout which conducts it into the bay, bushel or
barrel to which it rests above the floor on the side side the mill under the
barrel is about 12 inches wide and to reach the bottom of the barrel
to be cut in the left side the mill being to the wind barrel, the bottom of
which above the floor an another barrel to catch the headings
to store in front Yards high wide and long enough to fill the space
from the front to the wind barrel side wall is to be supported by 2 or 3
inch posts displaced across and to be hoisted up 29 inches from the bottom
where which a slide is made, a little inclining to the front by hoisting
or resting to conduct the headings to the front barrel between the barrel
and the side side being the chips or cockle to the barrel barrel barrel the
setting barrel by side the wind barrel 2 or 3 inch posts a displaced
across the top Yards from the ends, between which the hopper is made
striking it below this piece, the post piece supports the slide by 2
large wires, the upper barrel of set wall is rounded the back corner covered
with a back cover on below this a slide does that starts up the end
above the barrel, Next a shape that is attached to the timber which goes
through the bottom of the 3 inch space or outlet of the wind, Next a
wheel 3 inches in diameter 2 inches thick is to be made fast in the
bottom, the wheel is to be placed or mounted three eighth of an inch
deep and half inch wide commencing in the bottom carrying it
about 5 eighth of an inch to the side, from back to the bottom on a line
circle, then down to the left and so on, starting from 4 to 6 shakes to the

turning, so that, going once round, a small round iron stick is pushed to the ~~where~~ ^{where} in front plays into the crevise which lies between the ~~lips~~ ^{lips}. This shaking wheel may be made of wood or cast iron, & may be fitted out on a rim, with scotched iron bolts on each side of it. The mill may be cast iron gearing or wood and bands. So turning wheel of cast iron 26 inches in diameter, shaking wheel or jaw 34 inches a small pulley wheel on the shaft inside the turning wheel 16 inches in diameter, the wheel that turns the rolling screen & iron cast in diameter to go with a band by adding an extra wheel and placing the gearing on the other side the mill. So wheels may be much smaller for tightening the bands, by having ~~iron~~ ^{iron} ~~pinch bars~~ or screws and bolts. ~~These~~ ^{These} may be dampers to slide over the air holes if necessary to shut out the wind. The means of shaking the grains & the rolling screen constitute the principal. These claimed as an invention or improvement.
